United States Patent Office.

JOHN A. BURCHARD AND RICHARD TATTERSHALL, OF BELOIT, WISCONSIN.

Letters Patent No. 79,201, dated June 23, 1868; antedated February 12, 1868.

IMPROVEMENT IN GATES.

The Schedule referred to in these Letters Patent and making part of the same.

TO ALL WHOM IT MAY CONCERN:

Be it known that we, JOHN A. BURCHARD and RICHARD TATTERSHALL, of Beloit, Wisconsin, have invented certain new and useful Improvements in Gates; and do hereby declare that the following is a full and complete description thereof, reference being had to the accompanying drawings and letters of reference marked thereon, which are a part of this specification.

Figure 1 is a perspective view of the gate taken from the inside approach to the street.

Figure 2 is a side view of the double-inclined plane J and pitmen K.

Figure 3 is a vertical view of fig. 2.

Figure 4 is a side view of the ratchet e.

Figure 5 is a side view of the pulley D, pawl E, and stop f.

Figure 6 is a perspective view of the double pulley D d, pawl E, and stop f.

Figure 7 is a front view of the latch-post N, latches n, and stop p.

Figure 8 is a side view of fig. 7.

A A A represent the main frame of the gate.

B B are central standards of the gate, hung upon the tracks J J by the grooved rollers I I, and attached to the post of the main frame by the hinges and eyes m m'.

b b are horizontal bars or rods passing through the standards B B, and connected to the gate-frame b' b'.

J J are circular double-inclined planes, upon which the rollers I I travel in opening and closing the gates. The circular double-inclined planes J J are so constructed that the rollers I I traverse a down grade from the ends to the centre pivot, on which the said planes oscillate, thence to the ends on level planes in either opening or closing the gates. The outer ends of the circular planes are provided with stops to prevent the rollers I I from running off the ends of the said planes.

The horizontal shaft C C is provided with cranks, c' c', which are attached to the inner ends of the planes by pitmen K K.

The double pulley D d, provided with the pawl E, stop f, and weight G, revolve loosely upon the shaft C C, to which is rigidly affixed the ratchet e, which pulley is actuated by the cords h h and weight G. The pull-posts L L are placed at suitable distances from the gate. The cords h h are secured at opposite points in the grooved periphery of the pulley D, each of which passes around one-half of the circumference of said pulley, thence in opposite directions to the posts L L, thence through suitable pulleys connected to the caps of said posts, leaving the pulls H H of said cords h h pendent therefrom. The circular planes are supported by the arms O O. The gates are held closed by the latches n n, which are secured to the posts N by suitable bolts.

In closing, the catches attached to the frame of the gate b' b' pass under the latches n n, and in opening, the gates are raised above the said latches.

The gates may be held open by a similar device.

The post N is provided with suitable stops, p p, to secure the proper operation of said latches.

The gate is operated by a downward pull of the cords h h, causing the pawl E, affixed to the pulley D d, to engage with the rigid ratchet attached to the shaft C C, when, the pulling-force being continued, the shaft is revolved. The cranks being moved forward and upward, or in the line of an arc, actuate the pitmen, which thus raises the inward ends of the inclined planes, by the same operation sliding the gates upward, lifting them out of the latches n n and winding up the weight G, thereby putting the gates in position to open freely by their own gravity. On releasing the cord h, the weight G rotates the pulley D d to its normal position.

The gate is opened and closed by repeating the operation from either approach.

What we claim as our invention, and desire to secure by Letters Patent, is—

1. We claim broadly the employment of the double pulley D d, pawl E, ratchet e, weight G, and cords h h, when constructed, arranged, and operated for the purpose of operating a gate or gates.

2. We claim broadly the circular inclined plane J, when constructed and arranged substantially as herein

set forth and described, for the purpose specified; but we do not claim as new the oscillating-plane *J*, for that has already been secured to us by Letters Patent of the United States.

3. We claim the latches *n n* and stops *p p*, in combination with the inclined planes *J J*, shaft *C C*, cranks *c c*, pulley *D d*, cords *h h*, weight *G*, gate-standards *B B*, rods *b' b'*, and rollers *I I*, when the whole is constructed and arranged to operate substantially as herein described.

JOHN A. BURCHARD,
RICHARD TATTERSHALL.
